WILLIAM L. MCGRATH, OF ELMIRA, NEW YORK, ASSIGNOR TO ECLIPSE MACHINE COMPANY, OF ELMIRA, NEW YORK, A CORPORATION OF NEW YORK

ENGINE STARTER DRIVE

Application filed March 1, 1932. Serial No. 596,120.

This invention relates to engine starter drives and more particularly to a drive embodying a novel form of yielding driving connection and novel arrangements of the co-operating parts.

In commercial types of starter drive embodying a pinion threaded on a screw shaft for engaging an engine gear, a yielding driving connection for the pinion is provided in the form of a coiled spring anchored at its ends to the screw shaft and the shaft of the starting motor.

It has been found to be important in drives of this character that the anchoring pins for the ends of the springs be protected so far as possible from bending stresses resulting from the driving loads, and various expedients have been perfected for placing the pins under substantially pure shearing stresses during the driving operation in order to avoid overloading the pins.

Moreover, in some installations of this character, the idle positions of the screw shaft and pinion are determined by the length of the drive spring, and the longitudinal yield of the screw shaft to enforce meshing is provided for by spacing the convolutions of the drive spring to allow the requisite longitudinal compression thereof in case of tooth abutment between the pinion and flywheel. In the manufacture of such drive springs it is obviously important that the dimensions of the spring be held to close limits. This has been found to be somewhat difficult, particularly in the case of springs having comparatively widely spaced convolutions.

It is an object of the present invention to provide a novel engine starter drive embodying a coiled drive spring in which the spring is so formed as to transmit practically nothing but shear stresses to its anchoring pins.

Another object is to provide such a device embodying means for supporting the spring and limiting its deflection under load, such means being so formed as to avoid binding or the setting up of localized stresses in the members of the drive.

A further object is to provide such a device in which the drive spring may be comparatively closely wound whereby its capac-

ity may be increased while its overall dimensions are reduced.

It is another object of the invention to provide such a device which is so arranged that the drive spring draws the screw shaft 55 against a stop which determines its idle position, and the spring is arranged to stretch lengthwise during the operation of enforcing mesh between the pinion and flywheel gear.

Further objects and advantages will be apparent to those skilled in this art from the following description taken in connection with the accompanying drawing in which:

Fig. 1 is a side elevation partly in section of a preferred embodiment of the invention; 65

Fig. 2 is an end view on an enlarged scale of the drive spring thereof; and

Fig. 3 is a side view of said spring.

Referring first to Fig. 1 of the drawing there is illustrated a driving shaft 1 which 70 may be the extended armature shaft of a starting motor, not shown. The free end of the shaft 1 is preferably journaled as indicated at 2 in a housing a portion of which is indicated at 3, whereby the shaft is substantially relieved from bending stresses due to driving reactions. 75

A driven shaft in the form of a screw shaft 4 is freely journaled on the driving shaft 1 and carries threaded thereon an engine driving member in the form of a pinion 5 in position to be moved longitudinally into and out of engagement with a member of the engine to be started such as the flywheel gear 6. The outer or idle position of the pinion 5 is defined by the heel 7 of the threads on the screw shaft 4, and the pinion is normally retained in its idle position by suitable means such as a yielding detent 8 which is arranged to cooperate with an inclined shoulder 9 on the 80 screw shaft to form an anti-drift device for the pinion. 85

The driving shaft 1 has mounted thereon a driving head 11 having a smooth cylindrical outer surface, said head being suitably fixed 95 thereon as by means of a key 12 and a pin 13 traversing said driving head and entering a pilot opening 14 in said shaft. The driven shaft 4 has a driven head 15 suitably fixed thereon as by means of cooperating threads 100

16 and a pin 17 which is arranged to traverse registering openings 18 and 19 in said head and shaft respectively, but being too short to bind against the shaft 1. The driven head 5 15 is also formed as a smooth cylinder of the same diameter as the driving head 11 and is counterbored as indicated at 21 to receive a reduced extension 22 of said driving head whereby the two heads have a loose telescoping 10 joint therebetween.

According to the present invention, a yielding driving connection between the driving and driven heads is provided in the form of a coiled spring indicated generally at 23 having 15 a cylindrical body portion 24 and terminating in radial eyes 25 and 26 which are arranged to surround snugly the pins 13 and 17 and to be gripped thereby firmly to the driving and driven heads respectively. The 20 center distance between the eyes 25 and 26 when the spring is free is made equal to or slightly less than the center distance between the pins 13 and 17 when the device is assembled whereby the spring yieldably maintains 25 the driving and driven heads in abutting relation as shown, the two heads forming a smooth cylinder within the spring 23, the joint 27 therebetween being located substantially midway between the pins 13 and 17, and 30 said cylinder forming means for limiting the winding up of the spring 23 due to driving loads transmitted therethrough.

According to the present invention, the spring 23 is so formed that the pins 13 and 35 17 are subjected to substantially pure shearing stresses during the driving operation. As here illustrated, this is accomplished by forming the portion of the ends of the spring adjacent the anchoring pins so as to bear snugly 40 on the cylindrical surface of the heads for a substantial distance whereby bending stresses on the pins are prevented. As here illustrated, these inwardly displaced portions of reduced radius are quadrant or longer, and 45 it has been found in practice that these portions are preferably formed so that the spring bears on the heads at points from 90 to 120 degrees removed from the anchoring pins. The 50 quadrant end portions 28 and 29 of the springs are connected to the cylindrical body portion 24 thereof by sections 31 and 32 of intermediate curvature. These sections are 55 preferably substantially semi-circular in extent in order that the ends thereof may properly line up with the adjacent portions of the spring and the various portions will merge smoothly into each other.

The cylindrical body portion 24 of the 60 spring is formed with sufficient radius to allow the spring to wind up in performing its yielding driving function. The cylinder formed by the members 11 and 15, however, is adapted to support the convolutions of the 65 spring and prevent distortion thereof beyond

the elastic limit in case of abnormal stress applied thereto.

Referring particularly to Fig. 2 of the drawing, the quadrant terminal portion 29 is formed with a radius "r" equal to the radius 70 of the heads 11 and 15, and extends through an arc "a" which as illustrated is approximately 120 degrees from the axis of the eye 26. The body portion 24 of the spring is formed with a radius "t" which is sufficiently 75 greater than the radius "r" to allow the proper space 33 between the body of the spring and the surface of the cylindrical heads to permit the desired amount of winding up of the spring to take place. The body portion 24 of the spring is connected to the quadrant portion 29 by means of the intermediate portion 32 which is formed approximately with a radius "s" intermediate the radii "r" and "t" and offset from the axis of 80 the drive by a distance "o" equal to one half the difference between the radii "r" and "t". The intermediate portion 32 is formed to extend through the arc "b" which as illustrated is substantially 180 degrees whereby the ends 85 of the portions 32 merge smoothly into the ends of the quadrant portion 29 and the body portion 24.

It will be understood that the term "quadrantal" as used with reference to the terminal 90 portions of the springs is not intended to define an arc of exactly 90°, but is intended to include structures as illustrated which vary considerably from precisely a quarter of a circle. It will also be understood that due to 95 the large radial thickness of the spring material, and the stresses set up in winding the spring, the intermediate portion 32 may not be a true semi-circle, but the precise shape 100 of that portion is not important as long as it merges smoothly into the body and terminal portion of the spring, and the terms "semi-circle" and "radius" are therefore not intended to apply with geometric precision.

The eyes 25 and 26 of the spring are formed 105 with the inner edges 34 and 35 thereof curved on the radius "r" (Fig. 2) whereby they conform closely to the surfaces of the heads 11 and 15. It will readily be appreciated that 110 this close conformation of the terminal portions of the spring to the cylindrical surfaces of the heads will prevent any rocking motion of the ends of the springs on the cylinders during driving and thus prevent the application 115 of bending stresses to the anchoring pins. It has also been found that drive springs embodying the invention have a much longer life than drive springs now in general use but 120 without the end convolutions of reduced radius.

The convolutions of the springs are preferably formed of greater radial than axial thickness in order that the torque capacity of the spring may be large compared with its 125 resistance to extension, and thus large driving

loads may be carried without permanently distorting the spring, while the spring is comparatively limber with respect to tension applied thereto.

- 5 In the operation of the device, starting with the parts in the positions illustrated in Fig. 1, rotation of the shaft 1 by the starting motor in the direction of the arrow will cause the screw shaft 4 to be rotated by reason of 70
10 the connection through the driving head 11, spring 23 and driven head 15. The pinion 5, however, by reason of its inertia, will not immediately assume the rotation of the screw shaft and will therefore be traversed longitudinally into mesh with the engine gear 6. When the longitudinal motion of the pinion 5 is stopped by the shoulder 36 on the driven head 15, the pinion is compelled to rotate with the screw shaft whereby rotation is transmitted to the engine gear to crank the engine. 75
15
20

The loads transmitted through the spring 23 may cause the same to wrap down on the heads 11 and 15, but since the joint 27 between said heads is located under the middle 80
25 portion of the spring, this wrapping down does not cause a binding of the parts or set up localized stresses such as might occur if the joint were near either end of the spring where it might be gripped by the spring before the spring had been completely wrapped down to its limiting position. The spring 23 thus serves to form a suitable yielding driving connection for the cranking operation. 85
30

35 When the engine starts, the rotation of the engine gear 6 causes the pinion 5 to overrun the threaded shaft 4 whereby the pinion is traversed back to its normal position where it is retained by anti-drift means 8, 9.

40 If, during the meshing movement of the pinion 5, a tooth of the pinion should abut end to end with a tooth of the engine gear 6, further traversal of the pinion is momentarily interrupted whereby the screw shaft 4 will 90
45 be drawn away from the driving head 11 against the tension of the driving spring 23. The spring 23 is so designed, as above pointed out, as to yieldingly resist this endwise movement of the screw shaft 4 whereby the frictional resistance between the threads on the screw shaft and pinion is allowed to build up until it overcomes the friction between the ends of the teeth on the pinion and engine gear. When this takes place, the pinion 5 95
50 is rotated by the screw shaft 4 into proper indexed relation with the engine gear, whereupon the pinion is quickly drawn into meshing relation by the contraction of spring 23. The completion of the meshing of the pinion and the cranking operation then take place in the usual manner. 100
55

60 It will be seen that there is here provided a structure whereby the objects of the invention are accomplished as above set forth, but it will be understood that certain changes 105
65

may be made in the details of construction and arrangements of the parts without departing from the spirit of the invention as defined by the claims appended hereto. It will also be understood that although the invention is illustrated herein as applied to an "inboard" type of drive, it is equally applicable to the well known "outboard" type of drive. 70
75

What is claimed is:

1. In an engine starter drive, a rotatable shaft having a cylindrical driving head thereon, a driven shaft having a cylindrical head normally abutting and forming an extension of said driving head and yielding driving means for connecting said heads comprising a coiled spring adapted to loosely surround the cylinder formed by the driving and driven heads the end convolutions of the spring being displaced inwardly and reduced in radius so as to bear on said heads a substantial distance from the ends of the springs. 80
85
90

2. In an engine starter drive, a rotatable shaft having a cylindrical driving head thereon, a driven shaft having a cylindrical head normally abutting and forming an extension of said driving head and yielding driving means for connecting said heads comprising a cylindrical coiled spring adapted to loosely surround the cylinder formed by the driving and driven heads, the end convolutions of the springs being displaced inwardly and reduced in radius so as to bear on said heads at least 90 degrees from the ends of the springs. 95
100

3. In an engine starter drive, a rotatable shaft having a cylindrical driving head thereon, a driven shaft having a cylindrical head normally abutting and forming an extension of said driving head, and yielding driving means for connecting said heads comprising a coiled spring adapted to loosely surround the cylinder formed by the driving and driven heads, the end convolutions of the spring being displaced inwardly and reduced in radius so as to bear on said heads a substantial distance from the ends of the springs, said spring having substantially semi-circular portions of intermediate radius connecting the portions of reduced radius with the main body of the spring. 105
110
115

4. In an engine starter drive, a rotatable shaft having a cylindrical driving head thereon, a driven shaft having a cylindrical head normally abutting and forming an extension of said driving head and yielding driving means for connecting said heads comprising a coiled spring adapted to loosely surround the cylinder formed by the driving and driven heads with its ends anchored to said heads, the end convolutions of the spring being displaced inwardly and reduced in radius so as to bear on said heads at least 90 degrees from the ends of the spring the junction between the driving and driven heads being 120
125
130

- arranged substantially midway between the anchorages for the ends of the spring.
5. In an engine starter drive, a coiled driving spring comprising a cylindrical body portion, substantially quadrantal end portions of reduced radius terminating in radial eyes, and substantially semi-circular portions of intermediate radius connecting the end portions to the cylindrical body portion.
10. 6. In an engine starter drive, a coiled driving spring comprising a cylindrical body portion, substantially quadrantal end portions of reduced radius terminating in radial eyes, and substantially semi-circular portions of intermediate radius connecting the end portions to the cylindrical body portion, the inner edges of said radial eyes being formed as continuations of the inner edges of said quadrantal end portions.
15. 7. In an engine starter drive, a coiled driving spring having its convolutions substantially thicker radially of the spring than axially thereof, comprising a substantially cylindrical body portion, substantially quadrantal coaxial end portions of reduced radius, and substantially semi-circular portions of intermediate radius connecting the end portions to the body portion, said end portions terminating in radial eyes forming extensions of said quadrants.
20. 8. Starting mechanism for internal combustion engines comprising a driving shaft having a cylindrical driving head fixed thereon, a driven shaft journaled on the driving shaft having a cylindrical driven head fixed thereon and normally abutting said driving head, said heads having portions adapted to have a loose telescoping fit and forming together a smooth continuous cylinder, a member mounted on said driven shaft and connected thereto for longitudinal movement thereon into and out of engagement with a member of an engine to be started and rotation therewith to drive said engine member, and a coiled drive spring anchored at its ends to said driving and driven heads, at points substantially equally spaced axially from their joint line.
25. 9. Starting mechanism for internal combustion engines comprising a driving shaft having a cylindrical driving head fixed thereon, a driven shaft journaled on the driving shaft having a cylindrical driven head fixed thereon and normally abutting said driving head, said heads having portions adapted to have a loose telescoping fit and forming together a smooth continuous cylinder, a member mounted on said driven shaft and connected thereto for longitudinal movement thereon into and out of engagement with a member of an engine to be started and rotation therewith to drive said engine member, and a coiled drive spring anchored at its ends to said driving and driven heads, at points substantially equally spaced axially from their joint line.
30. 10. Starting mechanism for internal combustion engines comprising a driving shaft having a cylindrical driving head fixed thereon, a driven shaft journaled on the driving shaft having a cylindrical driven head fixed thereon and normally abutting said driving head, said heads having portions adapted to have a loose telescoping fit and forming together a smooth continuous cylinder, a member mounted on said driven shaft and connected thereto for longitudinal movement thereon into and out of engagement with a member of an engine to be started and rotation therewith to drive said engine member, and a coiled drive spring anchored at its ends to said driving and driven heads, at points substantially equally spaced axially from their joint line, and arranged to yieldingly maintain said ends in contact, said engine driving member being arranged to approach said spring in its engaging movement, whereby obstruction of such movement is yieldingly opposed by the tension of said spring.
35. 11. Starting mechanism for internal combustion engines comprising a driving shaft having a cylindrical driving head fixed thereon, a driven shaft journaled on the driving shaft having a cylindrical driven head fixed thereon and normally abutting said driving head, said heads having portions adapted to have a loose telescoping fit and forming together a smooth continuous cylinder, a member mounted on said driven shaft and connected thereto for longitudinal movement thereon into and out of engagement with a member of an engine to be started and rotation therewith to drive said engine member, and a coiled drive spring anchored at its ends to said driving and driven heads, at points substantially equally spaced axially from their joint line, the terminal quadrantal portions of said spring being arranged to conform to the cylindrical heads whereby the spring anchorages are placed under simple shear loads during the driving operation.
40. 12. Starting mechanism for internal combustion engines including a driving shaft having a substantially cylindrical driving head fixed thereon, a driven shaft having a substantially cylindrical driven head fixed thereon and normally abutting said driving head, a member mounted on said driven shaft and connected thereto for longitudinal movement thereon into and out of engagement with a member of an engine to be started, and for rotation therewith to drive said engine member, and a coiled driving spring anchored at its ends to said driving and driven heads, the terminal portions of said spring being formed to bear on said heads at points substantially spaced from their anchorages, and the intermediate portions of said spring being normally spaced radially from said heads.
45. 13. In an engine starter drive, a rotatable shaft having a driving head thereon, a driven

shaft having a driven head thereon, said heads being relatively movable in an axial direction and being extended by axially overlapping and relatively movable parts, and yielding driving means for connecting said heads comprising a cylindrical coiled spring surrounding said parts and drivingly connected to said heads, the end convolutions of the spring being displaced inwardly and reduced in radius so as to bear on said heads a substantial distance from the ends of the spring.

14. In an engine starter drive, a rotatable shaft having a driving head thereon, a driven shaft having a driven head thereon, said heads being relatively movable in an axial direction and being extended by axially overlapping and relatively movable parts, and yielding driving means for connecting said heads comprising a cylindrical coiled spring loosely surrounding said overlapping parts and drivingly connected to said heads, the end convolutions of the spring being displaced inwardly and reduced in radius so as to bear on said heads at least 90° from the ends of the spring.

15. In an engine starter drive, a rotatable shaft having a driving head thereon, a driven shaft having a driven head thereon, said heads being relatively movable in an axial direction and being extended by axially overlapping and relatively movable parts, and yielding driving means for connecting said heads comprising a cylindrical coiled spring surrounding said parts and drivingly connected to said heads, the end convolutions of the spring being displaced inwardly and reduced in radius so as to bear on said heads a substantial distance from the ends of the spring, said spring having portions of intermediate curvature connecting the portions of reduced radius with the main body of the spring and shaped so that contiguous portions of different curvature merge with each other smoothly and without abrupt changes in curvature.

16. A coiled driving spring for engine starter drives comprising a main body portion having coils of equal radius, substantially quadrantal end portions of reduced radius, and portions of intermediate curvature connecting said end portions with the main body of the spring and shaped so that contiguous portions of different curvature merge with each other smoothly and without abrupt changes in curvature.

In testimony whereof, I have hereunto signed my name.

WILLIAM L. McGRATH.
